UNITED STATES PATENT OFFICE

109,364

DESIGN FOR A SUIT ENSEMBLE

Morris Berger, New York, N. Y.

Application March 2, 1938, Serial No. 75,503

Term of patent 3½ years

To all whom it may concern:

Be it known that I, Morris Berger, a citizen of the United States of America, residing in New York city, in the Borough of Manhattan, county and State of New York, have invented a new, original, and ornamental Design for a Suit Ensemble, of which the following is a specification, reference being had to the accompanying drawing, forming part thereof, wherein,

The jacket section of the suit unit is contrastingly colored and matches the coat edging.

I claim:

The ornamental design for a suit ensemble, substantially as shown, and described.

MORRIS BERGER.
